UNITED STATES PATENT OFFICE.

ISRAEL KUSSNER, OF NEW YORK, N. Y.

SHOOTING-GALLERY TOY.

Application filed June 2, 1925. Serial No. 34,376.

To all whom it may concern:

Be it known that I, ISRAEL KUSSNER, a citizen of the United States, residing at New York, in the county of New York and State of New York, have invented certain new and useful Improvements in Shooting-Gallery Toys, of which the following is a specification.

This invention relates to games and toys and more particularly to a novel and improved, fascinating shooting gallery game whereby a number of objects are mounted so as to be struck and knocked over by a projectile, such as a small marble or bullet discharged from a spring gun, for instance.

One of the objects of my invention is to provide a light, portable shooting gallery game, in which a number of objects are individually mounted on a bar, whereby they may be struck and knocked over by a projectile, such as a marble or bullet, for instance, including provision for removing the marble or bullet from the bottom of the frame constituting the gallery.

In order to more fully understand and appreciate my invention, reference is had to the accompanying drawings, wherein,

Figure 1 is a front view, embodying my invention.

Figure 2 is a vertical, sectional view through the same.

Referring now to the drawings wherein like reference characters designate corresponding parts throughout all the views, 5 designates the floor or base and 6 the back or rear wall of a frame, which may be braced by a bent strip 7 so as to prevent the same frame from falling when said rear wall is struck by an object such as a marble or bullet. The front wall 8 is connected to the rear wall by suitable spacers 9, located near the top, said front wall being blocked out or cut away to expose the objects to be struck by the marble or projectile in the manner further to be described. Between the sides 10, 11, of the front wall, I have mounted a transversely extending rod or bar 12, on which a number of objects such as the representations of animals are 50 hingedly mounted. These objects 13 are hingedly connected as at 14 to the horizontal bar 12 whereby when said objects are struck, they will be knocked down to a horizontal position, as shown by the dotted lines in Figure 2, against a small leaf spring 12^a, said spring returning the object to its nor-

mal upright position. In addition to providing the objects 13, on the horizontal bar 12, I also provide a bell 13^a and separate and independent swinging elements, consisting of discs 15 on the ends of the thin rods 16, which are free to swing from the top of the front wall so that the marble or bullet may be discharged with the endeavor to strike the swinging disc. In the bottom of the frame, and between the front and rear walls, I provide a curved, runway 17, whereby the objects will roll down toward the opening 18 in the front wall 8 so that the said objects may be removed. A sliding plate 19 is adapted to close the opening 18 and when said plate is raised, the objects (marbles or bullets) 20 may roll out through the front wall and be again used.

Any suitable type of spring gun, for instance, as indicated by numeral 21 may be utilized to receive the marbles or bullets to be fired by the spring controlled rod 22. If so desired, the representation of miniature soldiers, or other objects provided with a spring controlled rod for firing the marble or bullet may be provided so that the said marble or bullet may be projected to knock down the objects 13 or strike the swinging disc.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claims.

Having thus described my invention, what I claim as new and desire to secure by United States Letters Patent is:—

1. A toy of the class described comprising a base, a rear wall and an open, spaced, front wall, a supporting shaft mounted between the sides of the front wall and across the opening thereof, a plurality of independent, hingedly connected objects carried by the shaft, a curved runway on the base between the front and rear wall and an opening in the bottom portion of the front wall whereby projectiles discharged at the said objects may be removed.

2. A toy of the class described comprising a base, a rear wall and an open, spaced, front wall, a stationary shaft mounted be-

tween the sides of the front wall and across the opening thereof, a plurality of hinged objects carried by the shaft, freely swingable members on the sides of the front wall,
5 a curved runway on the base between the front and rear walls, said front wall having an opening in the bottom and a sliding

plate for closing the said opening whereby projectiles discharged at the objects and falling between the said walls may be removed through the said opening. ¹⁰

In testimony whereof I affix my signature.

ISRAEL KUSSNER. [L.S.]
